F. POKORNÝ.
FOLDING UMBRELLA.
APPLICATION FILED AUG. 2, 1910.

973,207.

Patented Oct. 18, 1910.

UNITED STATES PATENT OFFICE.

FRANK POKORNY, OF NEW YORK, N. Y.

FOLDING UMBRELLA.

973,207.

Specification of Letters Patent. Patented Oct. 18, 1910.

Application filed August 2, 1910. Serial No. 575,170.

To all whom it may concern:

Be it known that I, FRANK POKORNY, a subject of the King of Hungary, and a resident of the city of New York, in the county 5 of New York and State of New York, have invented certain new and useful Improvements in Folding Umbrellas, of which the following is a specification.

The present invention relates to improvements in folding umbrellas, and more particularly to that class in which the ribs, braces and the staff or stick are composed of a plurality of slidably engaged sections.

One of the objects of the invention is to simplify and improve the construction and operation of the devices of this character, and to provide one which is of a very simple, strong, and durable construction, and easy to operate.

Another object of the invention is to provide an umbrella which may be folded into a very compact and small bundle, which can be carried in the pocket or satchel, the umbrella being in the form of a small cylindrical package only a few inches in diameter and a few inches in length.

With these and other objects in view, which will appear as the invention is better understood, the same consists in the construction, arrangement and combination of parts hereinafter fully described, pointed out in the appended claims, and illustrated in the accompanying drawings, it being understood that various changes may be made 35 in the size and proportion of the parts, and minor details of construction without departing from the spirit or sacrificing any of the advantages of the invention.

One of the many possible embodiments of the invention is illustrated in the accompanying drawings, in which:—

Figure 1 is a side elevation of the umbrella stick, one of the ribs and one of the brace pairs of the improved umbrella, showing them in their extended or open positions; Fig. 2 is a similar view showing the rib and the braces in their closed positions; Fig. 3 is a similar view showing all parts folded or collapsed; Fig. 4 is a plan view of one of the ribs; Fig. 5 is a section taken on line 5—5 of Fig. 4; and Fig. 6 is a vertical cross section of the umbrella stick in its extended position.

In the present embodiment of the invention, the staff or stick is composed of six tubular sections 6, 7, 8, 9, 10 and 11. Of

these the sections 8 and 9 are fixedly attached to each other and within each other, while the other sections are telescoped into the sections 8 and 9. It is, of course, obvious that the stick may consist of a greater or less number of sections. The stick sections are held in their extended positions, shown in Figs. 1 and 2, by means of spring catches 12, 12. The spring catch attached 60 to section 6 rests then upon the upper edge of the section 7, and the spring catch of the latter section engages the upper closed ends of the section 8 and 9. In a similar manner rests the spring catch of the section 9 upon 65 the upper edge of the section 10, and the catch of the section 10 upon the upper edge of the section 11. The construction of these spring catches need not be described, as the same is well known in the art. The disengagement of the stick sections from each other is prevented by suitable stops 12'. The lower end of the stick section 11 is provided with a suitable handle 13. To the section 7 of the stick is secured a notch disk 70 14, to which the inner ends of the ribs 15 are pivoted. A notch disk 16 is fastened to the section 8 of the stick, to which are pivotally attached the inner ends of the main stretchers 17, their outer ends being in a 75 similar manner attached to the ribs 15. The runner of the umbrella is indicated at 18, having attached thereto the inner ends of auxiliary stretchers 19, the outer ends of which engage pivotally the stretchers 17. 80

The rib is formed of three sections 20, 21 and 22, of which the sections 20 and 22 are slidably held upon the section 21. This latter section is of U-shaped cross section, having a partition 23 running throughout the 85 length thereof, whereby two channels 24 and 25 are formed therein. The section 20 slides into the channel 24, while the section 22 slides into the channel 25, when the ribs of the umbrella are collapsed. To prevent 90 the rib section 20 from telescoping into the section 21, when the umbrella is in its open position, a spring pressed locking lever 26 is pivotally attached at 27 to the rib section 21, its nose 28 engaging the end of the 95 rib section 20, while its free end 29 projects toward the stretcher 17, for a purpose hereinafter to be specified. The rib section 22 is prevented from telescoping into the section 21 by means of a spring stop 30, 100 fixedly attached at 30' to the rib section 21, and having an inwardly projecting finger

31 engaging the end of the section 22. An extension 32 of the spring stop projects into the channel 24 of the rib section 21 and into the path of the end of the rib section 20, in telescoping.

The stretcher 17 is made of two sections 33 and 34, which are pivotally secured together at 35. These stretcher sections and also the stretcher 19 are of U-shaped cross sections, and more particularly the cross section of the stretcher section 33, is somewhat larger than that of the section 34, while the cross section of the stretcher 19 is somewhat larger than that of the section 33, whereby, in closing the umbrella, the section 34 will be folded into section 33, and both sections into the stretcher 19.

The umbrella frame may be provided with a covering of any suitable material, which is attached to the outer ends or tips of the ribs and to the stick near to the notch disk 14, so that, when the umbrella is being collapsed, the covering can be folded without detaching the same from the frame.

When it is desired to close the umbrella from its position shown in Fig. 1 to that shown in Fig. 2, the spring catch 36 upon the stick section 8 is forced into the stick sufficiently to be disengaged from the runner 18. The runner can then be pulled downward toward the handle 13, whereby the umbrella will be closed in the usual manner.

To open the umbrella, that is to bring it from the position shown in Fig. 2 to that shown in Fig. 1 of the drawings, the runner 18 is taken hold of and pushed toward the notch disk 16, and until the lower end of the runner is brought to rest upon the pointed end of the spring catch 36.

When it is desired to fold the umbrella, or in other words to reduce its length shown in Fig. 2 to that shown in Fig. 3, first the spring catch of the stick section 6 is pressed inwardly, whereby the section 6 can be slid into section 7. In telescoping the section 6 into section 7, the lower end of the former will disengage the spring catch 12 of section 7 from the section 8, whereby the section 7 can be telescoped into the section 9, and at the same time the rib section 20 into the rib section 21. It will be observed that in closing the umbrella from the position shown in Fig. 1 to that shown in Fig. 2 of the drawings, the stretcher sections 33 will force the noses of the locking levers 26 out of engagement with the outer ends of the rib sections 20, allowing thereby the latter to slide into the sections 21. The outer ends of the rib sections 20 lift the projections 32 of the spring stops 30, and disengage thereby the fingers 31 of said stops from the inner ends of the rib sections 22, allowing them to slide into the sections 21. When the spring catch 12 upon section 10 of the stick is forced in-

wardly, the section 10 can be telescoped into section 11. In this position the bell 37 upon section 11 is brought into engagement with the outer ends of the rib sections 22, after which the section 10 is telescoped into the stick section 8; the spring catch 12 of the section 9 having been previously disengaged from the section 10 as the section 7 of the stick was telescoped into the section 9, in the same manner as the section 6 disengages the spring catch of the section 7 from section 8. The rib sections 22 telescope with the movement of the stick section 10. In order to extend the umbrella, obviously the reverse operations are necessary.

What I claim is:

1. In a folding umbrella, the combination with an umbrella stick made of a plurality of sections, of telescoping ribs each composed of an inner section pivotally connected to said stick, a middle section and an outer section, said inner and outer sections being slidably arranged lengthwise upon the middle sections, a notch disk secured to one of said stick sections, main stretchers pivotally connected to said notch disk and to the middle sections of said ribs, a runner slidably arranged upon said stick, and auxiliary stretchers connected to said runner and said main stretchers.

2. In a folding umbrella, the combination with an umbrella stick made of a plurality of sections, of telescoping ribs each composed of an inner section pivotally connected to said stick, a middle section and an outer section, said inner and outer sections being slidably arranged lengthwise upon the middle sections, a notch disk secured to one of said stick sections, main stretchers made of a plurality of sections pivotally connected to said notch disk and to the middle sections of said ribs, a runner slidably arranged upon said stick, and auxiliary stretchers connected to said runner and said main stretchers.

3. In a folding umbrella, the combination with an umbrella stick made of a plurality of sections, of telescoping ribs each composed of an inner section pivotally connected to said stick, a middle section and an outer section, said inner and outer sections being slidably arranged lengthwise upon the middle section, a notch disk secured to one of said stick sections, main stretchers pivotally connected to said notch disk and to the middle sections of said ribs, a runner slidably arranged upon said stick, auxiliary stretchers connected to said runner and main stretchers, means upon the middle sections of said ribs for holding the inner sections thereof in their extended positions, and means also upon the middle sections of said ribs for holding the outer sections of said ribs in their extended positions, said first named means being disengaged from said in-

ner sections as said umbrella is being closed and said second named means being disengaged from said outer sections when said inner sections are telescoped into said middle 5 sections.

4. In a folding umbrella, the combination with an umbrella stick made of a plurality of sections, of telescoping ribs each composed of an inner section pivotally connected to said stick, a middle section and an outer section, said inner and outer sections being slidably arranged lengthwise upon the middle section, a notch disk secured to one of said stick sections, main stretchers pivotally connected to said notch disk and to the middle sections of said ribs, a runner slidably arranged upon said stick, auxiliary stretchers connected to said runner and said main stretchers, locking levers upon the middle sections of said ribs for holding the inner sections thereof in their extended positions, and spring stops also upon the middle sections of said ribs for holding the outer sections of said ribs in their extended positions, 20 said locking levers being disengaged from 25

said inner sections by said main stretchers as the umbrella is being closed, and said spring stops being disengaged from said outer sections by said inner sections as said inner sections are telescoped into said middle 30 sections.

5. In a folding umbrella, a rib composed of a middle section, and two outer sections slidably arranged upon said middle section and adapted to telescope into said middle 35 section so as to lie side by side of each other.

6. In a folding umbrella, a rib composed of a U-shaped middle section having a partition running therethrough whereby two channels are formed therein, and two outer 40 sections slidably arranged in said two channels.

Signed at New York, in the county of New York and State of New York, this 26th day of July, A. D. 1910.

FRANK POKORNY.
